UNITED STATES PATENT OFFICE.

LADISLAUS ROBACZYNSKI, OF BROOKLYN, NEW YORK.

KNITTING-MACHINE.

1,185,244.

Specification of Letters Patent.

Patented May 30, 1916.

Application filed February 2, 1914. Serial No. 815,936.

To all whom it may concern:

Be it known that I, LADISLAUS ROBACZYNSKI, a subject of the Emperor of Austria-Hungary, residing in the borough of Brooklyn, county of Kings, State of New York, have invented certain new and useful Improvements in Knitting-Machines; and I do hereby declare the following to be a full, clear, and exact description of the invention, such as will enable others skilled in the art to which it appertains to make and use the same.

My invention relates to improvements in knitting machines. It is particularly adapted for use in connection with knitting machines of the flat type having straight racks.

One object of my invention is to provide a novel mechanism for reciprocating the head which operates the pattern and counting chains and which drives the counting cylinder.

A further object of my invention is to provide a novel, efficient and durable mechanism for controlling the operation of the counting cylinder.

Still another object of my invention is to provide novel means by which accurate adjustment of the lifting blocks on the counting cylinder may be easily and quickly obtained.

Other novel features of my invention are hereinafter fully described and claimed.

In the accompanying drawings, in which I have illustrated my invention applied to a knitting machine of the flat type, Figure 1 is a rear elevation of a flat type knitting machine provided with the preferred form of my invention. Fig. 2 is a plan view of the same, some of the parts being broken away, and some of the parts being omitted. Fig. 3 is an enlarged right elevation of a part of the machine, some of the parts being omitted for clearness. Fig. 4 is an enlarged front elevation of my improved controlling mechanism, parts being omitted or broken away. Fig. 5 is a vertical section on the line 5—5 of Fig. 4. Fig. 6 is a vertical section on the plane of the line 6—6 of Fig. 4. Fig. 7 is a vertical section on the plane of the line 7—7 of Fig. 4. Fig. 8 is a vertical section on the plane of the line 8—8 of Fig. 4. Fig. 9 is a vertical section on the plane of the line 9—9 of Fig. 4. Fig. 10 is a vertical section on the plane of the line 10—10 of Fig. 4. Fig. 11 is a fragmental

transverse vertical sectional view of a part of the counting cylinder and two of the lifting blocks carried thereby. Fig. 12 is a top view of the cylinder partly broken away, when it is in the position shown in Fig. 4.

Similar reference characters designate similar parts in the different views.

1 designates the main driving shaft of the machine, which may be rotated by means of a crank 2, or which may be driven by a pulley 3, when a clutch 4 operated by a handle 5, is thrown into operative position. Secured on the shaft 1 is a pinion 6 which meshes with a spur gear wheel 7, which is secured fast to a horizontal shaft 8 rotatably mounted in the frame 9.

A horizontally reciprocative carriage 10, Fig. 1, of the usual type is reciprocated over two inclined needle racks 11 and 12, by means of a rod 13 connected to a cross head 14, which is omitted in Fig. 2, but which, as shown in Fig. 1, is reciprocative on two horizontal parallel bars 15, which are supported by the frame 9. A pitman 16 has its ends pivoted respectively to the head 14 and

to a radially adjustable crank pin 17 carried on a bar 18 which is secured to the spur gear wheel 7. The front needle rack 11, in this particular type of machine, is adapted for being longitudinally shifted back and forth for cross stitching, by means of a cam 19 which is secured fast to a horizontal shaft 20, Fig. 1, rotatably mounted in the frame 9 and having secured to its forward end a ratchet wheel 21 provided on its periphery with two sets of ratchet teeth, 22 and 23, Figs. 3, 4 and 5, which are adapted to be engaged respectively by means of two pawls 24 and 25 which are pivoted to a horizontally reciprocative controlling head 26, which is slidably mounted in two bearings 28 by means of two horizontal parallel bars 27 with which said head 26 is provided.

The needle operating mechanisms for the racks 11 and 12 are carried in the boxes 29 with which the carriage 10 is provided in the usual manner. 30 designates the usual cotton or yarn carrying boxes which are slid respectively along the slide supports 31, carried by the frame 9 and slidably supporting the carriage 10, by the bolts 32 and 33, carried by the boxes 29, said bolts being alternately thrown into operative position by means of two horizontal bars 34 and 35, Fig. 2, which are pivoted at one set of ends

to a lever 36 pivoted to the carriage frame, said rods being actuated respectively by means of two stop pins 37 and 38, which are carried by a rocking yoke 39, Fig. 3, which is pivotally mounted on a horizontal stud, supported by the frame 9, said stud being designated by 40. A coil spring 41, Fig. 4 encircles the stud 40 and normally swings the yoke 39 in a clockwise direction, so that 10 the stop pin 38 will engage the rod 35 on the forward movement of the carriage 10. To rock the yoke 39 counter-clockwise so that the stop pin 37 will engage the rod 34, said yoke is provided with a crank 42, Fig. 3, 15 which is connected by a link 43 with a bar 44 which is pivoted on a horizontal stud 45 secured to the frame 9, see Figs. 3 and 4.

The free end of the bar 44 is swung upwardly by means of a block 46 which is secured to an endless chain 47, Figs. 3 and 4, which is used, as hereinafter described, for pattern and counting purposes. The chain 47 is mounted on a sprocket wheel 48, which is secured to a sleeve 49, Fig. 6, 25 which is rotatably mounted on a stud 50, secured horizontally to the frame 9 and which sleeve in turn has secured to it a ratchet wheel 51 which is adapted to be engaged by a pawl 52, which is pivoted to the 30 head 26. When the said head is reciprocated, the pawl 52 on its rearward movement will engage the ratchet wheel 51 and will move it clockwise one tooth, thereby rotating the sprocket wheel 48 one tooth, 35 and thereby advancing the chain 47 one link in the same direction.

Reciprocation of the head 26 is obtained by means of a horizontal rod 53, Figs. 2 and 3, which has its forward end pivoted to the 40 head 26, by means of a vertical pin 54 and has its rear threaded end fitted in a threaded hole provided in an eccentric strap 55 which embraces an eccentric 56 which is secured to the upper end of a vertical shaft 57, Fig. 3, 45 rotatably mounted in the frame 9 and having secured fast to its lower end a bevel pinion 58 which meshes with a bevel gear wheel 59, having twice the diameter of the pinion 58, and which is secured fast to the 50 shaft 8.

By means of the gearing just described, the eccentric 56 effects two complete reciprocations of the controlling head 26 for each complete reciprocation of the carriage 10. 55 The eccentric 56 is so set as to effect a forward movement of the controlling head 26 before and after the boxes 29 on the carriage are in operative position with reference to the needle racks. This arrangement permits the rack 11 to be shifted in both directions without injury to the needles.

I will now describe how the chain 47 controls the rocking of the cam shaft 20 by which the needle rack 11 is shifted. As is 60 shown in Fig. 3, the chain 47 is provided

with links of three different widths. Each of these links is adapted to support a horizontal pin 60, Figs. 3, 4 and 5, which is secured to the right hand side of a bar 61, which is pivoted on the stud 45, already referred to as having pivoted to it the bar 44. The bar 61 has rigidly secured to it a pin 62 which extends horizontally to the left and is adapted to bear against the under side of the pawl 24 so as to lift said pawl out of engagement with the teeth 22 of the ratchet wheel 21, and to bring into engagement with the teeth 23 thereof the pawl 25, which result is accomplished by means of a coil spring 63 which connects the pawls 24 and 25, and by its tension always tends to draw them toward each other and into engagement with the ratchet wheel 21. A spacing pin 64 fastened to the pawl 24 and having its lower end free from, but adapted to bear against the pawl 25, holds the pawls far enough apart, at all times, so that both pawls may be free from the ratchet 21, when the pin 60 is bearing against any one of the medium width links in the chain 47. 90

With the chain 47 having one of its narrowest links engaging the pin 60, the pawl 24 will be disposed so as to engage the ratchet wheel 21 and thereby rock the cam shaft 20 upon the forward movement of the 95 controlling head 26. At this time the pawl 25 will be free from said wheel, as shown in Fig. 5, the pawls being held in these positions by a coil spring 64, which is fastened to the pawl 24 and has its lower end secured to the frame 9.

When the chain 47 is positioned with any one of its medium width links engaging the pin 60, both pawls 24 and 25 will clear the ratchet wheel 21 and the rack 11 will not be 105 shifted in either direction on the forward movement of the controlling head 26.

When the chain 47 is positioned with any one of its widest links engaged with the pin 60, the pawl 24 will clear the wheel 21 and the pawl 25 will engage said wheel upon the forward movement of the controlling head 26 and will rock the cam shaft 20 clockwise, thereby shifting the needle rack 11 in the direction opposite to the direction in which 115 it was shifted through the intervention of the pawl 24.

It will be understood that if a chain 47 should be used having all links of the medium width, the pawls would not engage the 120 ratchet 21 and the rack 11 will not be shifted.

There is also provided, preferably, another and a shorter endless pattern chain 65, which, like the chain 47, has links of different width for supporting the pin 60 in different positions to effect rocking of the shaft 20 as already described, and which is mounted on a sprocket wheel 66 which is secured fast to a sleeve 67, Figs. 5 and 6, 130

which is rotatable on the sleeve 49 and has secured fast to it a ratchet wheel 68 which is adapted to be engaged by a pawl 69 which is pivoted to the controlling head 26 along 5 side of the pawl 52. When said controlling head is moved forward, and the pawl 69 is permitted to drop into engagement with the ratchet wheel 68, said ratchet wheel will be turned, and with it the sprocket wheel 66 and 10 chain 65, upon the rearward movement of the controlling head 26.

I will hereinafter describe the mechanism by which the pawls 52 and 69 are held against the force of gravity from respectively engaging the ratchet wheels 51 and 68. For preventing the ratchet wheels 51 and 68 from being turned upon the forward movement of the controller head 26, two pawls, Fig. 4, pivoted to the frame 9 and designated 15 by 70 and 71, respectively engage the ratchet wheels 51 and 68, said pawls being normally held engaged with said ratchet wheels by means of two springs 72 and 73 which are secured to a pin 74 fastened to 20 the frame 9.

I will now describe the counting cylinder and the mechanism which actuates it and controls its operation. 75 designates the counting cylinder which is secured fast to a 25 horizontal shaft 76 which is rotatably mounted in an inverted U-shaped bracket 77, which is secured to the frame 9. The cylinder 75 is provided with two annular peripheral grooves 78 and 79, the periphery of 30 the cylinder between said grooves being graduated into a number of numbered spaces, as shown in Fig. 12.

In the groove 78 are mounted a number of removable blocks 80, which have dove-tailed 35 lower ends, which are slidably fitted in the groove 78, which is also dove-tailed in cross-section. The blocks are rigidly held in the positions to which they are adjusted by pointed screws 81, the lower ends of which 40 are adapted to be seated respectively in a series of conical recesses 82, provided in the bottom of the groove 78. As is shown in Figs. 4 and 12, and also in Fig. 7, the groove 45 79 is also provided with similar conical recesses 82 adapted to receive securing screws 81 mounted in two stop blocks 83 and 84 respectively, the block 83 being located in the groove 79 opposite the zero space in the graduated part of the cylinder. Opposite to 50 this zero space, in the groove 78, no block is mounted, a space 85 being left at this point for the purpose referred to hereinafter.

The graduated space, as shown in Fig. 12, is provided with a transverse groove 86, next 55 to the zero space and connecting the grooves 78 and 79 to permit the insertion and removal of the blocks 80, 83 and 84.

A lever 87, which is secured fast to a horizontal shaft 88 rotatably mounted in the 60 bracket 77, is provided with a downwardly

extending projection 87', which is adapted to rest upon the blocks 80, or to drop into the space 85, whereby the lever 87 at its rear end is raised or lowered, thereby raising or lowering the pawl 52, by means of a vertical 70 rod 91 which is secured to a pin 89 mounted in a slot 90 in the rear end of the lever 87.

Pivoted on the shaft 88 is a lever 92 provided with a downwardly extending projection 93, which is adapted to be lifted and 75 held supported by the block 83, thereby lifting the rear end of the lever 92, so as to swing the pawl 69 out of engagement with the ratchet wheel 68, by means of a vertical 80 rod 94, the upper end of which is secured to the pawl 69, and the lower end of which is fastened to a pin 95 mounted in a longitudinal slot 96 in the rear end of the lever 92.

From the foregoing it will be understood 85 that, with the projection 87', resting on the blocks 80, the lever 87 will hold the pawl 52 out of engagement with the ratchet 51. At such times the chain 47 will not be driven, upon the rearward movement of the controller head 26. When the counting cylinder 75 is disposed in the position shown in Figs. 4 and 6, the projection 87' of the lever 87 will be in the space 85, which is opposite to the stop and lifting block 83. At this 90 time the rear end of the lever 87 will be lowered and the pawl 52 will be engaged with the ratchet wheel 61, and said ratchet wheel will be turned on the rearward movement of the head 26, thereby driving the 100 chain 47 step by step as long as the lever 87 is in said lower position.

When the lever 92 is supported by the block 83, the pawl 69 will be lifted free from the ratchet wheel 68 and the chain 65 105 will not be driven by the sprocket wheel 66 which is secured to the ratchet wheel 68. As soon as the cylinder 75 is turned the space of one block so as to drop the lever 92, the pawl 69 will engage the ratchet wheel 110 68 and the chain 65 will be driven, thereby controlling shifting of the needle rack through the intermediary of the pin 60, as described with reference to the chain 47. Thus it will be understood, there being only 115 one lifting block in the groove 79, the block 84 in the portion which passes under the lever 92 not being high enough to lift said lever, that when the lever 92 is raised, the lever 87 will be lowered and vice versa. The chains 47 and 65 will thus be alternately 120 driven.

I will now describe how the chain 47 controls the operation of the cylinder 75. Secured fast on the shaft 76 to which the cylinder 75 is secured, are two ratchet wheels 97 and 98, Figs. 4 and 10, having reversely disposed teeth adapted to be respectively engaged by two pawls 99 and 100, which are pivoted on a horizontal stud 101, which 130

is secured to the lower end of a vertical lever 102, Fig. 3, which is pivoted on a horizontal bolt 103 mounted in a bracket 104, which is secured to the frame 9. The upper end of the lever 102 is pivoted to a link 105, which is pivoted to the controller head 26. When the controller head 26 moves forward, the shaft 76 will be rotated, and with it the counting cylinder 75 in a direction which is dependent upon which one of the pawls 99 or 100 is in operative engagement with its ratchet wheel.

If the pawl 99 is engaged with the ratchet 97, the rotation of the cylinder 75 will be in a clockwise direction, as viewed in Fig. 10. With the pawl 100 engaged with the ratchet wheel 98, the rotation of the cylinder 75 will be in a counter-clockwise direction. It will be understood that both pawls 99 and 100 should not be in operative position at the same time. The engagement of the pawls 99 and 100 with their respective ratchet wheels 97 and 98 is controlled by four cams 106, 107, 108 and 109, which are loosely mounted on the shaft 76, Fig. 4.

The pawls 99 and 100 are normally drawn toward each other by means of a coil spring 110, Fig. 10. Extending horizontally to the left from the pawls 99 and 100 respectively, are two pins 111 and 112 which are adapted to be engaged by either of the cams 106, 107 or 108 so as to hold disengaged the pawls which carry them from their respective ratchet wheels.

The cam 106 is provided with peripheral recesses 113 and 114 which, when said cam is turned to the position shown in Fig. 10, permit the pins 111 and 112 to move to positions in which their respective pawls will be in operative positions. To swing the cam 106 to the position shown in Fig. 10, it has pivoted to it a link 115 which is pivoted to a crank 116 secured fast to a rock shaft 117, mounted horizontally in the bracket 77, and having secured fast to its right end an arm 118, Fig. 3, which is adapted to be depressed by any one of four pins 119, which extend horizontally to the right from a ratchet wheel 120, which is loosely mounted on the shaft 76. Step by step counter clockwise movement of the ratchet wheel 120 is obtained by means of a pawl 121, which is pivoted on the stud 101 already referred to.

From the foregoing it will be understood that when the controller head 26 is reciprocated, the pawl 121 will cause rotation of the ratchet wheel 120, at such times as said pawl is engaged with said ratchet wheel. It will be further understood that, when the ratchet wheel 120 is rotated, the pins 119 will consecutively depress the arm 118, thereby, four times, during a revolution of the ratchet wheel 120, swinging the cam 106 to the position shown in Fig. 10, thus en-

abling one of the pawls 99 or 100 to rotate the cylinder 75 four numbered spaces for each complete revolution of the ratchet wheel 120, providing that other parts of the mechanism permit the pawls 99 and 100 to swing into the operative position.

The arrangement of the parts is such that when the pawl 121 is engaged with the ratchet wheel 120, said wheel will be turned one tooth, corresponding to a part of a revolution equal to one numbered space on the cylinder 75, for each complete reciprocation of the controller head 26. To hold the ratchet wheel 120 against retraction, there is provided a pawl 122, Fig. 3, which is pivoted on a stud 123 carried by the bracket 77, a spring 124 serving to hold said pawl in the operative position.

In order that the ratchet wheel 120 may be manually turned, it has engaging it a pawl 125, Fig. 3, which is pivoted on a bar 126, which in turn is pivoted on the shaft 76. A pin 127 mounted in the bracket 77 serves to limit the downward movement of the bar 126. By lifting this bar up and forcing it down, the pawl 125 will rotate the ratchet wheel 120. Said pawl is held engaged with said ratchet wheel by means of a spring 128 carried by the bar 126.

To retract the cam 106 from the operative position shown in Fig. 10 to the position in which said cam will force apart pins 111 and 112, the rock shaft 117 has secured to it an arm 129 to which is connected a coil spring 130, which is also connected to the stop pin 127, which for this purpose extends through the arm of the bracket 77 in which said pin is mounted.

To lift the pawl 121 from engagement with the ratchet wheel 120 when the lever 87 is lowered into the space 85 of the counting cylinder 75, for the purpose to be hereinafter explained, the shaft 88, to which the lever 87 is made fast, has secured to it an arm 131, Fig. 3, which, when the arm 131 is depressed, as shown in Fig. 3, swings downward one end of a lever 132, the other end of which carries a pin 133 which lifts the pawl 121 clear of the ratchet wheel 120. The lever 132 is pivoted on a stud 134 secured to the bracket 77.

The cam 107, which is of the same form as the cam 106, is provided with recesses 135 and 136 adapted respectively to receive therein the pins 111 and 112, to permit the pawls 99 and 100 swinging to the operative positions at the proper times. To swing the cam 107 from the position shown in Fig. 9, in which position the pins are held out of the operative positions, said cam 107 has pivoted to it a link 137, which is also pivoted to a lever 138, pivoted on the stud 45, and adapted to be engaged by a pin 139 which is carried by the long chain 47. When said pin swings the lever 138, upon

the driving of the chain 47, the cam 107 will be swung to the position shown in dotted lines in Fig. 9, in which position the pins 111 and 112 will be free, so far as the cam 107 is concerned, to move to the operative positions. After the pin 139 has passed by the lever 138, a coil spring 140 secured to the lever 138 and to a pin 141, in the bracket 77, retracts the lever to the position shown 10 in solid lines in Fig. 9.

The cams 108 and 109 are employed to reverse the direction of rotation of the cylinder 75. To effect this the cam 108 is provided with two recesses 142 and 143, Fig. 15, 8, adapted to respectively receive the two pins 111 and 112 so as to permit one, only, of the pawls 99 and 100, to pass at one time to the operative position. The recesses 142 and 143 are, therefore, arranged so that, 20 when the cam 108 is in the position shown in solid lines in Fig. 8, the pin 111 is free to swing to the operative position, while the pin 112 is held from moving to the operative position. When the cam 108 is swung 25 to the position shown in dotted lines in said figure, the pin 112 will be permitted to move to the operative position and the pin 111 will be held from moving to such position.

The determination of which position the 30 cam 108 is to occupy is controlled by two pawls 144 and 145, which are pivoted on the stud 101 and are normally forced toward each other by a coil spring 146, and are adapted respectively to enter two peripheral notches 147 and 148 in the periphery of the disk 149, which is secured concentrically to the cam 108. The pawls 144 and 145, when moved forwardly, will, one or the other, engage the disk 149 and turn it, 35 with the cam 108, to place one or the other of the pins 111 or 112 in the operative position. Which pawl 144 or 145 engages the disk 149 is controlled by the cam 109, which is adapted to engage two pins 150 and 151, 40 carried respectively by rigid extensions 152 and 153 of the pawls 144 and 145. The cam 109 is provided with two peripheral recesses 154 and 155 adapted to receive respectively the pins 150 and 151, the arrangement of said recesses being such that, when the cam 109 is in the position shown in Fig. 7, the pin 150 will be held, while the pin 151 will be free to enter the recess 155, thereby permitting the pawl 145 to engage 45 the disk 149, so as to turn it in a clockwise direction upon the forward movement of the pawl. When the cam 109 is shifted counterclockwise from the position shown in Fig. 7, the pin 150 will enter the recess 50 154, while the pin 151 will be held out of the recess 155. The pawl 144, at this time, can engage the disk 149 upon the forward movement of the pawl. Two spring actuated pawls 156 and 157, pivoted on a stud 158 secured to the bracket 77, respectively

limit the counter-clockwise movement of the cams 108 and 109, by entering notches 159 and 160 provided respectively in said cams.

For reversing the direction of rotation of 70 the counter cylinder, which is effected by the pawls 99 and 100 operating in the two ratchet wheels 97 and 98 through the intermediary of the cams 108 and 109, as above described, the cam 109 has mounted 75

in it a pin 161, which is located in a slot 162 provided in a bar 163, which is pivoted on a pin 164 secured in the bracket 77. The blocks 83 and 84 extend laterally to the right of the cylinder 75. When the cylinder 80 is rotated clockwise to the position shown in Fig. 7, the block 83 will have struck the bar 163 and swung it and the cam 109 to the position shown in Fig. 7.

The forward movement of the stud 101 with 85 the pawls 144 and 145 will cause the pawl 145, which is in operative position by reason of the pin 151 carried thereby being in the recess 155 of the cam 109, to turn the cam 108 to the position shown in dotted lines 90 in Fig. 8, at which time, the pawl pin 112 will be in the recess 143 of the cam 108, and the pawl 100 will be engaged with the ratchet wheel 98. The forward movement

of the controller head 26 will retract rearwardly the pawl 100, thereby rotating the ratchet wheel 98, and with it the cylinder 95 75, in a counter-clockwise direction. Succeeding reciprocations of the pawl 100, through the intervention of the stud 101, 100 the lever 102, link 105 and controller head 26 will cause the counting cylinder 75 to be rotated counterclockwise until the block 84 strikes the bar 163 and swings it, and the cam 109, until the pin 150 can enter the 105 notch or recess 154 in said cam, at which time the pin 151 will have been forced by the cam 109 so that the pawl 145 will be disengaged from the disk 149. The pawl 144 will then engage the disk 149, and the cam 108 will be shifted to the position shown in solid lines in Fig. 8, at which time the pin 111 will enter the recess 142, and the pawl 99 will be brought into engagement 110 with the ratchet wheel 97, thus reversing the movement of the said ratchet wheel and with it the cylinder 75. The cylinder 75 will now rotate clockwise, as viewed in Fig. 6 and Fig. 7 until the block 83 strikes the bar 163 and swings it and the cam 109 to the 115 original position, shown in Fig. 7.

The operation of my invention is as follows: The driving shaft 1 having been started in the manner hereinbefore described, reciprocation of the carriage 10 will 125 be effected by the mechanism already described, and the controller head 26 will be reciprocated by means of the eccentric 56, thereby effecting shifting of the rack 11 130 through the intermediary of the pawls 24

and 25, ratchet wheel 21, cam shaft 20 and cam 19 in a manner dependent upon the style of the pattern chains 47 and 65.

In setting up the machine for operation, 5 the cylinder 75 is turned to the initial position, shown in Figs. 6 and 7, and also in Fig. 4, in which position the lever 87 will have its projection 87' in the space 85, opposite the graduation zero space. At this 10 time the lever 92 will rest on the lifting and stop block 83, which will be in the position shown in Fig. 7, in which position the cam 109 will be forced to the position shown in Fig. 7.

15 At starting the ratchet wheel 120 will be turned to the position shown in Fig. 3 in which the arm 118 will be depressed by one of the pins 119, thereby rocking the shaft 117 to the position shown in Fig. 10, in which 20 position the cam 106 will permit either one of the pawls 99 and 100 to be forced to the operative position with reference to the ratchets 97 and 98 which drive the shaft 76 in one direction or the other, thereby rotating the cylinder 75 in case that the cam 107 is in the dotted position shown in Fig. 9. Which one of the pawls 99 and 100 will engage its ratchet wheel will depend upon the position of the cam 108, and as already 25 described, the position of this cam is dependent upon the position of the cam 109. With the cam 109 in the position shown in Fig. 7, which is the starting position, the cam 108 will be turned to the position shown in dotted lines in Fig. 8, thereby permitting the pawl 100 to engage the ratchet wheel 98.

At the time of starting the long chain 47 is set in a position on the sprocket wheel 48 such that the pin 139, carried by the chain 47, will strike against and will have lifted the lateral arm 165 of the lever 138 so that the cam 107 will be in the dotted position shown in Fig. 9.

Upon the rearward movement of the head 45 26, the lever 87 being in the space 85 of the cylinder 75, in the starting position, the pawl 52 being in engagement with the ratchet wheel 51, said ratchet wheel will be turned the distance of one tooth, thereby advancing 50 the chain 47 one link, so that the pin 139 releases the arm 165 of the lever 138, which lever is immediately retracted by the spring 140, Fig. 3, to the position shown in Fig. 9, in which position the cam 107 will 55 have been swung to the position shown in solid lines in Fig. 9, thus holding apart the pins 111 and 112, which are carried respectively by the pawls 99 and 100, and thereby preventing the engagement of said pawls 60 with the ratchet wheels 97 and 98 until the arm 165 of the lever 138 has again been engaged by the pin 139.

As the pawl 52 is retracted by the head 26, the stud 101, carried by the lever 102, 65 and moved forward by the link 105 when the

head 26 moves rearwardly, will be carried forward as will the pawls 99 and 100, which are carried by said stud. Thus, while the pin 139 in the chain 47 is carried from the initial position, in which it supported the arm 165 in a raised position, the cylinder 75 will not be advanced one number, for the reason that the spring 140 will have retracted the lever 138 to the position shown in solid lines in Fig. 9, before the head 26 starts on its forward movement and retracts the pawls 99 and 100.

For the above reasons the chain 47 will be advanced by the reciprocation of the head 26 until the pin 139 again strikes and raises the arm 165 of the lever 138. During the time that the chain 47 is making the circuit, the machine will be knitting the border of the garment. During this time, the lever 87 will be in the lower position shown in Fig. 3, thereby permitting a spring 166, which is connected to the arm 131 and to a pin 167, to swing downward the arm 131, thereby lifting the pawl 121 out of engagement with the ratchet wheel 120 by means of the lever 132. Said ratchet wheel will, therefore, remain in the position shown in Fig. 3 with one of the pins 119 holding depressed the arm 118.

After the border of the garment has been completed, the pin 139 of the chain 47 will have raised the arm 165, thereby swinging the cam 107 to the position shown in dotted lines in Fig. 9. Upon the next forward movement of the controller head 26, the pawl 52 will slip over the ratchet wheel 51, but the pawl 100 will be forced into engagement with the ratchet wheel 98, and will turn this ratchet wheel, together with the cylinder 75 one number in a counter clockwise direction, as viewed in Figs. 6, 7 and 10. This movement of the counting cylinder 75 will cause the pawl 52 to be raised clear of the ratchet wheel 51 by reason of the lever 87 being lifted out of the space 85 of the cylinder. At the same time, the lever 92 will drop from the lifting block 83, thereby permitting the pawl 69 to engage the ratchet wheel 68.

Upon the rearward movement of the controller head 26, the pawl 69 will turn the ratchet wheel 68, thereby driving the short chain 65 through the intermediacy of the sprocket wheel 66, which is secured on the sleeve 67 that carries the ratchet wheel 68. The knitting of the body of the garment will now begin.

Succeeding reciprocations of the head 26 will drive the short chain 65 step by step, thereby rotating the cylinder 75 in a counter clockwise direction, as viewed in Figs. 6 and 7, until the stop block 84 on said cylinder strikes the bar 163 and forces it and the cam 109 in a counter clockwise direction until the pin 150 enters the recess 154 and the pin 151 is forced from the recess 155. This, 130

as hereinbefore described, will cause the cam 108 to be shifted to the position shown in solid lines in Fig. 8, in which position the pawl 99 will be brought into engagement with the ratchet wheel 97 and the pawl 100 will be disengaged from the ratchet wheel 98. These movements of the reversing mechanism will cause the reciprocations of the controller head 26 to impart a step by step clock-wise movement to the cylinder 75 and the ratchet wheels 97 and 98, as viewed in Figs. 7 and 10. This step by step movement will be controlled, however, by the cam 106, which in turn will be controlled by the ratchet wheel 120 and the arm 118. As soon as the cylinder 75 moved one number counter clockwise from the initial position, the pin 119 will have moved from the arm 118 owing to the action of the pawl 121, which will have been permitted to engage the ratchet wheel 120 as soon as the lever 87 was lifted by the first step of the counting cylinder 75. As soon as the arm 118 was released from the pin 119, the spring 130 will have rocked the shaft 117 in a counter clockwise direction, as viewed in Fig. 10, until the cam 106 engaged and forced apart and away from the ratchet wheels 97 and 98 the pawls 99 and 100.

30 Succeeding oscillations of the lever 102 by the controller head 26 will effect step by step movement of the ratchet wheel 120 through the intermediacy of the pawl 121, until the next pin 119 strikes and depresses the arm 118, at which time, the cam 106 will be swung to the position shown in Fig. 10, thereby permitting either one of the pawls 99 or 100 to engage its ratchet wheel, thereby imparting rotary movement to the cylinder 75 a distance of one number.

40 From the foregoing it will be understood that for each complete revolution of the ratchet wheel 120, the counting cylinder 75 will be turned four numbers for the pins carried by said ratchet wheel.

When the cylinder 75 starts on its reverse clockwise movement, it will continue this movement until the stop and lifting pawl 83 has reached the initial position shown in Fig. 6, and also in Fig. 4. At this time the lever 87 will drop into the space 85, thereby permitting the pawl 52 to engage the ratchet wheel 51. At the same time, the lever 92 will be lifted by the block 83, thereby disengaging the pawl 69 from the ratchet wheel 68.

During the time that the small chain 65 has been running, the body of the garment will have been knitted, and the pin 139 will 50 have held the arm 165 in the elevated position, the chain 47 having stopped its movement just prior to the beginning of the travel of the chain 65.

As soon as the lever 87 has dropped into the space 85, the pawl 121 will be lifted from

the ratchet wheel 120. Upon the first rearward movement of the head 26, the pawl 52 will turn the ratchet wheel 51 one tooth, thereby driving the chain 47 one link, so as to again move the pin 139 away from the arm 165 in the manner already described, after which the various operations described will be repeated.

After the pin 139 has been released from the arm 165, and the chain 47 has started on its circuit, the block 46 carried thereby will lift the bar 44, thereby swinging the yoke 39, in the manner already described, so as to put into operation the box 30 which carries the cotton. As soon as the chain 47 has advanced another link, the block 46 will pass from under the bar 44, and the yoke 39 will be retracted by the spring 41 to the position for knitting yarn.

The block 46 may be placed at any desired point on the chain 47. In the relative position which it bears to the pin 139, as shown in the drawing, Fig. 3, the block 46 will cause the cotton thread to be inserted by the knitting mechanism adjacent to the beginning of the border. If it is desired to have the cotton thread inserted in about the middle of the border of the garment, the pin 139 may be placed in a hole 168, which is provided in one of the links of the chain 47, almost diametrically opposite from the block 46, as shown in Fig. 3.

From the above description, it will be understood that, upon starting the machine, the counting cylinder 75 is turned with the shaft 76 to the position shown in Figs. 4 and 6. Upon the driving shaft 1 being driven, the chain 47 having been placed on the sprocket wheel 48, with the pin 139 holding the arm 165 in the elevated position, the long chain 47 will first be made to travel a circuit, during which time the knitting mechanism will knit the border and insert a layer of cotton. After the chain 47 has completed its circuit, it will stop, while holding the arm 165 elevated, after which the short chain 65 will take up the work of controlling the pattern of the knitting, and the counting cylinder will begin to rotate in a counter clockwise direction, as viewed in Fig. 6, the step by step rotation of the counting cylinder being controlled by the pawl and ratchet mechanism, which is operated by the lever 102.

After the counting cylinder 75 has been rotated to a position in which the stop block 84 will have shifted the reversing mechanism, the counting cylinder will reverse its direction of movement from a counter clockwise to a clockwise direction, and will continue this clockwise movement until it has returned to the initial position shown in Fig. 6, at which time it will stop, and one garment will have been completed, so far as the knitting of the body and border is con-

cerned. The chain 47 will then begin to travel, and the knitting of the border for another garment will commence.

It will be understood that blocks 80 may 5 be omitted from the groove 78 to suit the style of knitting desired. It will also be understood that some of these blocks or others like them may be inserted in the groove 79. Instead of having the chains 47 and 65 10 working alternately, it may be desired, for certain patterns, to start the machine with the counting cylinder 75 not in the initial position shown in Fig. 6, and with the pin 139 out of contact with the arm 165 of the 15 lever 138. With the machine started in this manner, the cylinder would not run, nor would the chain 47, and the work produced would be all of one style or pattern, such as would be produced with the use of the 20 small chain alone. Or, if desired, the groove 79 could be filled with blocks, in which case the large chain and cylinder would work and the small chain would remain still.

By providing the conical seats 82 in the 25 grooves 78 and 79 of the counting cylinder, no skill or care is required to secure an accurate adjustment of the blocks in said grooves. If the blocks are positioned in approximately correct positions, the pointed 30 screws 81, bearing upon the inclined counter sinks or recesses 82, upon being tightened, will bring the blocks to accurately correct positions.

I do not limit my invention to the structure shown and described, as modifications 35 thereof, within the scope of the appended claims, may be made without departing from the spirit of my invention.

Having thus described my invention, what 40 I claim and desire to secure by Letters Patent, is:—

1. In a knitting machine, a reciprocative needle operating carriage, a shifting needle rack, an endless pattern chain, a reciprocative longitudinally slidable controller head, 45 mechanism including a ratchet wheel for operating said chain, a pawl carried by said head and adapted to engage said ratchet wheel, means operated by said head for shifting said rack, means controlled by said chain for controlling said shifting means, an eccentric, means operated by said eccentric for reciprocating said head, and driving means for reciprocating said carriage and 55 for rotating said eccentric.

2. In a knitting machine, a reciprocative needle operating carriage, a shifting needle rack, an endless pattern chain, a reciprocative longitudinally slidable controller head, 60 mechanism including a ratchet wheel for operating said chain, a pawl carried by said head and adapted to engage said ratchet wheel, means operated by said head for shifting said rack, means controlled by said 65 chain for controlling said shifting means,

an eccentric, means operated by said eccentric for reciprocating said head, and driving means for reciprocating said carriage and for rotating said eccentric twice during each reciprocation of said carriage.

3. In a knitting machine, a needle operating carriage, racking means including two pattern chains and a reciprocative longitudinally slidable head, means operated by said head for alternately driving said chains, 70 means controlled by one of said chains for controlling said chain driving means, and means for reciprocating said carriage and for reciprocating said head twice during each reciprocation of said carriage.

4. In a knitting machine, a needle operating carriage, racking means including two pattern chains and a reciprocative longitudinally slidable head, means operated by said head for alternately driving said chains, 75 means controlled by one of said chains for controlling said chain driving means, an eccentric, means operated by said eccentric for reciprocating said head, and driving means for reciprocating said carriage, and 80 for rotating said eccentric twice for each reciprocation of said carriage.

5. In a knitting machine, a reciprocative needle operating carriage, racking mechanism including a pattern chain, a reciprocative longitudinally slidable head and means operated by said head for driving said chain, means controlled by said chain for controlling said chain driving means, an eccentric, means operated by said eccentric for reciprocating said head, and means 95 for reciprocating said carriage and for rotating said eccentric twice during each reciprocation of said carriage.

6. In a knitting machine, a reciprocative 100 needle operating carriage, two pattern chains, two ratchet wheels, a reciprocative longitudinally slidable head, two pawls carried by said head for respectively operating said ratchet wheels, means operated by 105 said ratchet wheels for respectively alternately driving said chains, means actuated by one of said chains for controlling the engagement of said pawls with said ratchet wheels, and means for reciprocating said carriage and for reciprocating said head twice during each reciprocation of said carriage.

7. In a knitting machine, a reciprocative 110 needle operating carriage, two pattern chains, two ratchet wheels, a reciprocative longitudinally slidable head, two pawls carried by said head for respectively operating said ratchet wheels, means operated by 115 said ratchet wheels for respectively alternately driving said chains, means actuated by one of said chains for controlling the engagement of said pawls with said ratchet wheels, an eccentric, means operated by said eccentric for reciprocating said head, and 120

125 130

means for reciprocating said carriage and for rotating said eccentric.

8. In a straight knitting machine, a reciprocative needle operating carriage, a reciprocating longitudinally slidable head, two endless chains, a counting cylinder, means actuated by said head for alternately driving said chains, means actuated by said head for rotating said cylinder, means controlled by one of said chains for controlling said cylinder rotating means, means actuated by said cylinder for controlling said chain driving means, and means for reciprocating said carriage and said head.

15 9. In a knitting machine, a needle operating carriage, a reciprocating head, two endless chains, a counting cylinder, means actuated by said head for rotating said cylinder, means actuated by said head for driving said chains, means actuated by said cylinder for controlling said chain driving means so as to alternately drive said chains, means controlled by one of said chains for controlling the cylinder rotating means, and 25 means for reciprocating said carriage and said head.

10. In a straight knitting machine, a reciprocative needle operating carriage, two endless chains, a counting cylinder, driving means for reciprocating said carriage, means actuated by said driving means for rotating said cylinder and alternately driving said chains, means controlled by one of said chains for controlling the rotating 35 of said cylinder, and means controlled by said cylinder for controlling the driving of said chains.

11. In a knitting machine, a needle operating carriage, two endless chains, a counting cylinder, driving means for reciprocating said carriage, means actuated by said driving means for rotating said cylinder and for independently driving said chains, means controlled by one of said chains for controlling the rotating of said cylinder, and means actuated by said cylinder for controlling said chain driving means so that they may be alternately driven.

12. In a knitting machine, a needle operating carriage, an endless chain, a counting cylinder, driving means for reciprocating said carriage, means actuated by said driving means by which the cylinder may be rotated in either of two directions and by 55 which said chain may be driven, means controlled by said chain for controlling the rotation of said cylinder, and means actuated by said cylinder for controlling the driving of said chain.

60 13. In a knitting machine, a needle operating carriage, driving means for reciprocating said carriage, an endless chain, a counting cylinder, means actuated by said driving means for rotating said cylinder and for driving said chain, means actuated

by said chain for controlling the rotating of the cylinder, and means actuated by said cylinder for controlling the driving of the chain and for controlling the cylinder rotating means.

70 14. In a knitting machine, a needle operating carriage, driving means for reciprocating said carriage, a reciprocating head, means operated by said driving means for reciprocating said head, a rotary ratchet wheel, a pawl carried by said head and adapted to engage and rotate said ratchet wheel, an endless chain, means actuated by said ratchet wheel for driving said chain, a rotary cylinder, means actuated by said cylinder for controlling the engagement of said ratchet wheel by said pawl, means actuated by said head for rotating said cylinder, and means by which said chain controls the cylinder rotating means.

85 15. In a knitting machine, a needle operating carriage, a reciprocative head, driving means for reciprocating said carriage and said head, an endless chain, a ratchet wheel, means actuated by said ratchet wheel for 90 driving said chain, a pawl carried by said head, and adapted to engage and rotate said ratchet wheel, a counting cylinder, means actuated by said head for rotating said cylinder in opposite directions, means actuated by said cylinder for controlling the engagement of said ratchet wheel by said pawl, and means controlled by said cylinder for controlling the reversal of movement of said cylinder by said cylinder rotating 100 means.

16. In a knitting machine, a reciprocating head, a counting cylinder, two endless chains, two ratchet wheels, means actuated by said ratchet wheels for independently 105 driving said chains, two pawls carried by said head and adapted to respectively engage said ratchet wheels, means actuated by said head for rotating said cylinder, means actuated by said cylinder for respectively 110 controlling said engagement of the ratchet wheels by said pawls, and means operated by one of said chains for controlling the cylinder rotating means.

115 17. In a knitting machine, a counting cylinder, means for rotating said cylinder alternately in opposite directions, means controlled by the cylinder for controlling the direction of its rotation, an endless chain, means for driving said chain, and means operated by said chain for controlling the starting and stopping of said cylinder rotating means.

120 18. In a knitting machine, a counting cylinder, two ratchet wheels, two pawls adapted for engagement with and for rotating said ratchet wheels respectively, means for reciprocating said pawls, means actuated by said cylinder for independently 125 controlling the engagement of said pawls 130

with said ratchet wheels, two endless chains, means operated by said ratchet wheels for respectively driving said chains, means for rotating said cylinder, and means operated by one of said chains for controlling the starting and stopping of said cylinder rotating means.

19. In a knitting machine, a counting cylinder having a peripheral groove provided in its bottom with a tapering counter sink, a block adapted for mounting in said groove and for circumferential movement therein, and held by the cylinder from outward radial movement, and provided with a screw-threaded radial hole therethrough, and a screw fitted in said hole and adapted to have its inner end bear against the counter sunk portion of the cylinder.

20. In a knitting machine, a counting cylinder having a peripheral groove having under cut sides and provided in its bottom with a tapering counter sink, a block slidably fitted in said groove and provided with a radial screw-threaded hole therethrough, and a screw fitted in said hole and adapted to have its inner end mounted in said counter sink.

21. In a knitting machine, a counting cylinder having two peripheral grooves, each provided with under cut sides, and provided each in its bottom with a tapering counter sink, a transverse groove connecting said two grooves and adapted to have passed therethrough one or more blocks to be mounted in either of said grooves.

22. In a knitting machine, a counting cylinder having two peripheral grooves, each dovetailed in cross section and each provided in its bottom with a plurality of tapering counter sinks disposed around the periphery of the cylinder, the cylinder having means by which blocks fitted to said grooves may be mounted in or removed from said grooves.

23. In a knitting machine, a rotary shaft, a counting cylinder secured fast to said shaft, two ratchet wheels having oppositely disposed teeth and secured fast to said shaft, a reciprocating head, means for reciprocating said head, two pawls adapted to respectively engage said two ratchet wheels, means actuated by said head for reciprocating said pawls, means controlled by said cylinder for controlling the engagement of said pawls

with said ratchet wheels, two endless chains, means operated by one of said chains for controlling the engagement of said pawls with said ratchet wheels, means for independently driving said chains, means controlled by said cylinder for controlling the operation of said chain driving means, and means by which said pawls are controlled to permit of their engagement periodically with said ratchet wheels during the reciprocations of said head.

24. In a knitting machine, a needle operating carriage, a ratchet driven racking device, a control operating head, pawls operated by said head for operating said racking device during one excursion of said head, counting mechanism, a pawl operated by said head for operating said counting mechanism during the excursion of the head in the other direction, and means for reciprocating said carriage and for so reciprocating said head that its reversals of movement will occur during the excursions of said carriage.

25. In a knitting machine, a needle operating carriage, ratchet driven pattern chains, a step by step counting mechanism, a control operating head, pawls operated by said head for driving said ratchets, a pawl operated by said head for operating said counting mechanism during movement of said head in one direction, the pawls operated by said head being operative when the head moves in the opposite direction, and means for reciprocating said carriage and for reciprocating said head so that its reversals of movement occur during excursions of said carriage.

26. In a knitting machine, a needle rack, a needle operating carriage, a longitudinally sliding control head, means operated by said control head for shifting said rack, an eccentric, means operated by said eccentric for reciprocating said head, and means for reciprocating said carriage and for rotating said eccentric twice during each reciprocation of said carriage.

In testimony whereof I affix my signature, in presence of two witnesses.

LADISLAUS ROBACZYNISKI.
